UNITED STATES PATENT OFFICE.

ELIJAH H. NOSTRAND, OF JAMAICA, NEW YORK, ASSIGNOR TO COX, NOSTRAND & GUNNISON, INC., OF BROOKLYN, NEW YORK, A CORPORATION OF NEW YORK.

SHADE HOLDER.

Application filed April 24, 1924. Serial No. 708,638.

This invention relates to a shade holder and the novelty consists in the adaptation and arrangement of parts as will be more fully hereinafter pointed out.

There are many types of shade holders on the market adapted to receive and hold rigidly in position a glass shade. There are also shade holders having flexible or yielding retaining or supporting members but neither of these types of devices provide means for holding a shade in position against accidental dislodgment and at the same time having sufficient yield in the retaining means to allow for the variation in the sizes. My device supplies this need in the art having both a flexible supporting means and a positive lock to prevent possible dislodgment of the shade as well as means for permitting the quick placing and removal of the shade from the holder.

In the drawings Figure 1 is a perspective of the shade holder embodying my device, with the shade in position, and being broken away for convenience in illustration. Figure 2 is a bottom plan view of my device. Figure 3 is a vertical section on the line 3—3 of Figure 2. Figure 4 is a detail of the movable support member as shown in Figure 2 with the concealed parts in dotted outline. Figure 5 is an enlargement of the section of Figure 3 embodying the movable support member. Figure 6 is a detail of the movable support member showing the unlocked position in dotted outline. Figure 7 is a detail of a way of mounting the rigid support members. Figure 8 is a detail of another way of mounting the movable support member.

In the drawings 8 is a shade holder or shell having a circular base rim 9 in which are adapted to be rigidly secured, so that they project on the inside, rigid support members 10 which are so spaced that they are less than one-third of the circumference of the base rim 9 apart and in the same relative position from the edge of the base rim 9; in a position substantially opposite the middle of the space between the rigid support members 10 is a movable support member 11. The movable support member 11 consists of a tubular member 12 rigidly secured to the base rim 9 in which is mounted a plunger member 13 having a flared stop member 14 on its inner end and a handle 15 rigidly secured to its outer end. A spring

16 is mounted over the plunger 13 being secured at its inner end at 17 to the plunger 13 and at its outer end to the tubular member 12. The tubular member 12 also has a bayonet lock slot 18 cut therein and a pin 19 rigidly secured to the plunger 13 is adapted to register in said lock slot and the inner end of said slot 18 has a locking pocket 20 in which there is sufficient play to permit the pin 19 to move sufficiently to take care of the variation in the size of the shade 21 as it is placed in the shade holder. The spring 16 has a twist therein before it is secured at 17 and to the tubular member 12 so that normally the pin 19 is always thrown in a clockwise direction so that it will register in the pocket 20. The rigid support members 10 may be secured as shown in Figure 2 being riveted at 22 or may have threaded pin members 23 adapted to receive and hold threaded heads 24 so that they can be placed in position or removed readily as may be desired.

When it is desired to place the shade 21 in the holder 8 or remove it therefrom it is only necessary to take hold of the handle 15 and turning the same counter-clockwise release the pin 19 from the pocket 20, then pull out on the handle 15 thereby compressing the spring 16 and removing or placing the shade 21 in position as may be desired. The handle 15 may then be released whereupon the spring 16 will return the plunger 13 to its normal supporting position and the twist in the spring 16 will return the pin 19 to the pocket 20 thereby locking the plunger 13 against accidental pressure outward so that the accidental removal or sliding from position of the shade 21 is not possible. It will be noted that the pocket 20 is sufficiently large to permit the pin 19 and the plunger 13 to move yieldably on the spring 16 to effect a yielding compression of the plunger 13 on the shade 21 thereby preventing breaking or cracking and also allowing for the slight variations in exact size and shape of the shade 21.

When removing from or replacing the shade 21 in the holder 8 the manner of mounting rigid support members 10 relatively close together will materially assist in simplifying the operation as the lip of the shade 21 can easily be slipped under the two supports 10 and, as the movable support member 11 is directly opposite, the other side of the lip of the shade 21 can be

easily and quickly slipped into place. It is thus seen that for purposes of mounting the shade 21 the rigid supports 10 together form one bearing or resting point and the movable support 11 a second resting point and there is no third point to be negotiated.

The rigid support members 10 and the movable member 11 may be constructed so that they can be quickly and easily mounted in a shade holder by merely drilling holes in the base rim 9 at the suitable intervals described so that in this way shade holders already on the market may be utilized and changed to my construction by this simple expedient. The construction of rigid support members 10 adapted for this use are shown in Figure 7 in which 23 is a threaded pin member adapted to pass through the hole drilled in the rim 9 and secured rigidly in place together with the support member 10 by means of a knurled nut 24 adapted to screw on to the pin 23 and be set up in the usual way by means of pliers so that the rigid support members 10 will be secured in position for use against possible dislodgment. The movable support member 11 when used in this manner may be constructed as shown in Figure 8 in which the tubular member 12 has a shoulder 25 adapted to rest against the rim 9 on the exterior as the member 11 is placed in the hole bored in the rim 9 for this purpose and the tubular member 12 also has an external threading over which a nut 26 is adapted to be threaded so as to lock said movable support member 12 rigidly in position in the shell 8. Otherwise the construction of the movable support member 11 will be the same as already described.

It is apparent that many variations in the particular construction of the movable support member and in the fixed or rigid support members may be made without departing from the spirit and scope of my invention.

I claim:

1. In a shade holder the combination of a shell, two support members rigidly mounted inside the shell near the base and a movable third support member mounted inside the shell near the base normally in a supporting position, automatic means for restoring said third supporting member to

supporting position when moved from the same comprising a tubular member rigidly secured in the side of said shell near the base, a plunger mounted in said tubular member having a spring around the same one end of which is secured to the plunger and the other end to the tubular member, a handle at the outer end of said plunger and a stop member at the inner end thereof.

2. In a shade holder the combination of a shell, two support members rigidly mounted inside the shell near the base and a movable third support member mounted inside the shell near the base normally in a supporting position, automatic means for restoring said third supporting member to supporting position when moved from the same comprising a tubular member rigidly secured in the side of said shell near the base, a plunger mounted in said tubular member having a spring around the same one end of which is secured to the plunger and the other end to the tubular member, a handle at the outer end of said plunger and a stop member at the inner end thereof, and automatic means for locking said third supporting member against accidental movement from said supporting position.

3. In a shade holder the combination of a shell, two support members rigidly mounted inside the shell near the base and a movable third support member mounted inside the shell near the base normally in a supporting position, automatic means for restoring said third supporting member to supporting position when moved from the same comprising a tubular member rigidly secured in the side of said shell near the base, a plunger mounted in said tubular member having a spring around the same one end of which is secured to the plunger and the other end to the tubular member, a handle at the outer end of said plunger and a stop member at the inner end thereof and automatic means for locking said third supporting member against accidental movement from said supporting position consisting of a pin rigidly mounted in said plunger, a bayonet lock in said tubular member and a twist in said spring adapted to throw said pin into said lock.

In testimony whereof I affix my signature.

ELIJAH H. NOSTRAND.
